UNITED STATES PATENT OFFICE.

JEAN A. MATHIEU, OF PORT LEYDEN, NEW YORK.

PROCESS OF ELECTRO-DEPOSITING NICKEL.

SPECIFICATION forming part of Letters Patent No. 320,377, dated June 16, 1885.

Application filed April 21, 1882. (No specimens.)

To all whom it may concern:

Be it known that I, JEAN A. MATHIEU, of Port Leyden, in the county of Lewis and State of New York, have invented a new and useful 5 Improvement in Baths for Electro-Deposition of Nickel, of which the following is a specification.

My invention consists of a process of electro-depositing nickel by means of a solution of 10 propionate of nickel.

To make the bath I make a solution of propionate of nickel, either by dissolving oxide of nickel in propionic acid or in any other way of attaining the same result.

15 The articles to be plated with nickel are prepared and placed in the bath in the manner now commonly in use, and an electric current is passed through the bath in the ordinary manner. The solution gives best results

20 at a strength of about 5° Baumé. Any regular electric current will answer in the process;

but a current from a dynamo is preferable, and the strength of the current may vary.

I do not claim in this application anything described and claimed in my application filed 25 April 21, 1882, Serial No. 59,090.

What I claim as my invention, and desire to secure by Letters Patent, is—

The process of electro-deposition of nickel herein described, consisting in placing the 30 article to be coated with nickel in a bath consisting of a solution of propionate of nickel, connecting said article with the negative pole, and an anode in the bath with the positive pole of a generator of electricity, and passing 35 an electric current through said bath, substantially as described.

JEAN A. MATHIEU.
